UNITED STATES PATENT OFFICE.

GUY P. THURBER, OF PITTSBURGH, PENNSYLVANIA, ASSIGNEE, BY MESNE ASSIGNMENTS, TO AUTOMATIC TRAIN CONTROL & SIGNAL COMPANY, OF PITTSBURGH, PENNSYLVANIA, A CORPORATION OF DELAWARE.

AUTOMATIC BRAKE-VALVE.

1,142,383.

Specification of Letters Patent.

Patented June 8, 1915.

Application filed June 22, 1911. Serial No. 834,742.

To all whom it may concern:

Be it known that I, GUY P. THURBER, of Pittsburgh, Pennsylvania, have invented a certain new and useful Automatic Brake-
5 Valve, of which the following is a specification.

The invention relates particularly to automatic systems of train control such for instance as shown in my pending applications Serial Nos. 389,887, filed Aug. 23, 1907, and 461,141, filed November 5, 1908, and the object of the invention is to provide simple and efficient mechanism for use in connection with such systems for automatically controlling the operation of the
10 brakes.

The invention accordingly consists of what I have termed an automatic brake valve which under certain conditions acts to cause a "service" application of the brakes, and under certain other conditions to cause an "emergency" application of the brakes.
20

Briefly stated my invention comprises: a main passage and a normally open valve
25 controlling same, an exhaust passage leading from one side of the main passage, a normally closed exhaust valve controlling said passage, operating means for said valve arranged to close the main valve and open the
30 exhaust valve, a supplemental exhaust passage extending from the exhaust side of the main passage, a normally closed valve in the supplemental exhaust passage, and means for opening the supplemental exhaust valve. The means for operating the
35 valves may vary. Preferably, however, the valves are controlled by a fluid-actuated device.

Various other features and objects of the
40 invention will appear as the specification proceeds.

In the accompanying drawings I have illustrated a preferred embodiment of the invention, but I would have it understood
45 that various changes and modifications may be made therein without departing from the spirit and scope of the invention.

In the drawings: Figure 1 is a longitudinal sectional view of an automatic brake valve embodying my invention, the parts being shown in the normal running position. Fig. 2 is a similar view with the parts shown in the position when an emer-
50

gency application of the brakes is being made.

Like reference characters refer to like parts throughout the several views.

For convenience in manufacture and assemblage, the device is preferably made in three separate parts, 1, 2 and 3, 3 being 60 the valve casing provided, as clearly shown, with a main passage therethrough. For the purpose of controlling flow through said passage, the same is provided with a partition 4 having a valve seat 4' therein, and a valve 5 is arranged for engagement with said valve seat. The opposite ends 6 and 7 of the main passage are connected respectively to the engineer's valve and to the train line of the air brake system. The 70 valve 5 which controls the main passage is preferably carried by a stem 10 which is arranged to reciprocate in a bore in the neck portion 8 of the section 2.

Communicating with the one side or end 75 (7) of the main passage, there is an exhaust passage 16', which, when the parts are in the position shown in Fig. 2, forms in connection with the port 16 a direct means of escape from the one end of the main passage. Controlling this exhaust passage there is an exhaust valve 12 arranged to seat against the valve seat 11. The two valves 5 and 12 are so arranged that when one is closed the other shall be open, and for this purpose the exhaust valve 12 is preferably also carried upon the valve stem 10, substantially as shown.
80

Different means may be employed for controlling the operation of the valves, but 90 preferably this means is in the form of a pressure-actuated device, such as the piston 14, which, as shown, is engaged upon the end of the valve stem 10 and works within the cylinder 9. This pressure-actuated device may be arranged to operate in either one of two ways. One method is to have pressure normally present upon the pressure-actuated device to hold the main valve normally open, so that when pressure is released the main valve will be closed, and the other way is to have the pressure-actuated device normally free of pressure and to supply the pressure only when the main valve is to be closed. This latter is the 95 100 form here illustrated, for it will be evident

that when pressure is supplied to the head of the piston through the opening 13 in the top of the cylinder, the piston will be forced down, thereby carrying the main valve 5 into engagement with its seat, and opening up the exhaust valve 12. With this form of the invention it is necessary to provide some means for returning the valves to the opposite position, with the exhaust valve closed and the main valve open. This means is, as shown, preferably in the form of a spring 15.

To explain the operation of the device as thus far described: the parts are normally 15 in the position shown in Fig. 1, with the main valve open and the exhaust valve closed. The end 6 of the main passage is connected to the engineer's valve, and the end 7 of said passage is connected to the train line so that in this normal position of the parts the main passage provides a direct means of communication between the train line and the engineer's valve. The engineer may thus, by reducing the pressure in the 20 train line through the agency of the engineer's valve, apply the brakes in the usual way. As it is well understood in the art, how, in an ordinary air brake system the reduction of pressure in the train line causes 25 an application of the brakes, it is not necessary to explain here the precise means by which this is accomplished. It will be seen, therefore, that under ordinary conditions the engineer has perfect control of his train 30 and can, by means of the engineer's valve, control the setting and the release of the brakes without any interference from the automatic brake valve. When, however, the train approaches a danger zone and passes into a so-called caution zone preceding the danger 35 zone, the automatic brake valve is actuated to cause an application of the brakes independent of any action on the part of the engineer. Means are, therefore, provided in 40 the system with which the train is equipped for opening up actuating fluid to the piston of the automatic brake valve when the train enters a caution zone. The means for thus admitting the pressure to the piston forms 45 no part of the present invention, but it may be remarked that such means is preferably in the form of a magnet valve like that disclosed in my pending application Serial No. 632,052. It being understood that pressure 50 is admitted to the top of the piston, it will be seen that the piston will be forced down to the position shown in Fig. 2, in which case the main valve is closed to cut off further communication between the engineer's valve 55 and train line, and the exhaust valve is opened to permit the fluid under pressure in the train line to escape out through said exhaust passage 16' and the exhaust port 16. The reduction of pressure in the train 60 line thus provided for causes an application 65

of the brakes, this being what is known as a service application. When the train enters a danger zone, however, it is desirable that the application of the brakes be made more sudden. In other words, that an "emergency" application should be made. Accordingly I have provided for an additional and more sudden exhaust of the train line pressure when the train enters a danger zone. This additional exhaust is preferably 70 provided by way of what I have termed a supplemental exhaust passage which includes the passage 19 leading from the same side of the main passage as the first exhaust passage out through the ports 28 in the chamber 17. This supplemental exhaust passage is controlled by a supplemental exhaust valve 24 mounted within the neck 18 of the chamber 17, and arranged to engage a valve seat 25. The supplemental exhaust valve is 75 carried upon a valve stem 23 and the same is guided in its movements by having the inner end 26 of said valve stem engaged in bore *a* in bushing 27, said bushing having ports *b* therein forming a continuation of the supplemental exhaust passage. This supplemental exhaust valve is also preferably controlled by a fluid-actuated device, and the same is here shown as a diaphragm 20 secured within the chamber 17. In the form 80 illustrated the parts are so arranged that when pressure is present upon the diaphragm, the same will be deflected to open the supplemental exhaust valve, substantially as shown in Fig. 2. The pressure is supplied to the diaphragm through the opening 21 in the head 20' of the chamber 17. Means are provided for ordinarily holding the supplemental exhaust valve closed, the same consisting in the present instance 85 of a spiral spring 22.

It has been explained above how a service application of the brakes is accomplished by the closing of the main valve and the opening of the exhaust valve. When it is 90 desired to make an emergency application of the brakes, as when the train enters a danger zone, the supplemental exhaust valve also is opened, substantially as shown in Fig. 2, by admitting pressure to the top of the diaphragm 20, whereby the supplemental exhaust passage provides an additional means of escape for the pressure in the train line.

Pressure relieving ports 1' are preferably 95 provided in the cylinder at the under side of the piston therein, so that any air beneath the piston may escape when pressure is applied to the top of the piston for actuating the same. It is desirable to regulate the parts so that the automatic brake valve will be actuated at a certain pressure, and this I have provided for by arranging a bypass 1" extending from a port 1' opening 100 into the cylinder above the piston to a port 105

1^b which in the normal position of the piston opens into the cylinder beneath the piston. Thus when the pressure is turned on to the top of the piston a certain percentage 5 escapes around through the bypass and out the relief ports 1'. The pressure necessary to shift the piston over may be governed by means of a needle valve 1° interposed in the bypass which may be secured and locked in 10 position by means of the lock nut 1^a. To suppose an example, this controlling valve may be so regulated that of say 125 pounds pressure entering the cylinder, 100 pounds may be permitted to escape through the bypass, whereby only 25 pounds will be actually effective to move the piston to close the main valve and open up the exhaust valve. It will be evident that this controlling valve thus regulates not only the pressure 15 at which the piston will be actuated but also the speed of movement of the piston since the greater the effective pressure naturally the greater will be the speed of movement. The port 1^b is preferably disposed so that the same will be closed by the piston when the piston has been forced all the way down so as to cut off further waste of air through the bypass, substantially as shown in Fig. 2.

30 Having thus described the invention, what is claimed is:

1. An automatic brake valve comprising a valve casing having a main passage therein, a valve controlling said passage, an exhaust passage leading from one end of the main passage, an exhaust valve controlling the exhaust passage, fluid-pressure-operated means controlling operation of said main and exhaust valves, a supplemental exhaust passage 35 communicating with the same end of the main passage as the first exhaust passage, a supplemental exhaust valve in said supplemental exhaust passage, and a pressure-actuated device controlling operation 40 of said supplemental exhaust valve.

2. An automatic brake valve comprising a valve casing having a main passage therein, an exhaust passage communicating with one end of the main passage, a valve stem, a 50 valve on said stem controlling the main passage, an exhaust valve arranged on said stem to close the exhaust passage when the main passage is open, fluid-pressure-actuated means connected with the valve stem 55 for operating the same, a supplemental exhaust valve in communication with the exhaust side of the main passage, and a fluid-pressure-operated device controlling operation of said supplemental exhaust valve.

60 3. In combination, a valve casing having a main passage therein, a valve controlling said passage, an exhaust passage communicating with one end of the main passage, an exhaust valve controlling the exhaust passage and arranged to be closed when the

main valve is open, means for operating said valves, a supplemental exhaust passage communicating with the exhaust side of the main passage, a supplemental exhaust valve controlling said supplemental exhaust passage, and means for operating said supplemental exhaust valve. 70

4. In combination, a valve casing having a main passage therein, a valve controlling said passage, an exhaust passage communicating with one end of the main passage, an exhaust valve controlling the exhaust passage, means for operating said valves whereby when the one valve has been opened the other will be closed, a supplemental exhaust passage extending from the same end of the main passage as the first exhaust passage, a supplemental exhaust valve controlling said supplemental exhaust passage, and a fluid-actuated device controlling operation 80 of said supplemental exhaust valve. 85

5. In combination, a valve casing having a main passage therein, a valve controlling said passage, an exhaust passage extending from one side of the main passage, an exhaust valve controlling said exhaust passage, said valves arranged so that when one is open the other will be closed, a fluid-pressure-actuated device connected with the valves for operating the same, a supplemental exhaust passage extending from the exhaust side of the main passage, a supplemental exhaust valve in said supplemental exhaust passage, and means for operating 90 said supplemental exhaust valve. 95

6. In combination, a valve casing having a main passage therein, a valve controlling said main passage, an exhaust passage extending from one side of the main passage, an exhaust valve controlling the exhaust passage, a valve stem on which the main and exhaust valves are arranged so that when the one is open, the other will be closed, a piston on the end of the valve stem, a cylinder inclosing said piston, means for conducting fluid under pressure to said piston, a supplemental exhaust passage connected to the exhaust side of the main passage, a supplemental exhaust valve controlling the supplemental exhaust passage, a fluid-pressure-actuated device connected with the supplemental exhaust valve for operating the same, and means for conducting fluid under pressure to said last-mentioned fluid-actuated device. 105 110

7. In combination, a valve casing having a main passage therein, a valve stem and a valve carried thereby controlling said passage, an exhaust passage extending on one side of the main passage, an exhaust valve on the valve stem controlling said exhaust passage, a fluid-actuated device connected with the valve stem, means acting on the valve stem to normally hold the exhaust valve closed and the main valve open, means 115 120 125 130

for conducting fluid under pressure to the fluid-actuated device, a supplemental exhaust passage extending from the same side of the main passage as the first exhaust passage, a supplemental exhaust valve controlling said supplemental exhaust passage, means for normally holding the supplemental exhaust valve closed, a fluid-actuated device controlling operation of the supplemental exhaust valve, and means for conducting fluid under pressure to said last-mentioned fluid-actuated device.

8. In combination, a valve casing having a main passage therein, a valve stem, a valve carried thereby and arranged to control flow through the main passage, an exhaust passage extending from one side of the main passage, an exhaust valve on the valve stem arranged to control the exhaust passage, means acting on the valve stem to normally hold the exhaust valve closed and the main valve open, a fluid-pressure-actuated device connected with the valve stem, means for conducting fluid under pressure to said device, a supplemental exhaust passage extending from the exhaust side of the main passage, a supplemental exhaust valve controlling the supplemental exhaust passage, means for normally holding the supplemental exhaust valve closed, a diaphragm connected with the supplemental exhaust valve for controlling operation of the same, and means for conducting fluid under pressure to the said diaphragm.

35 9. In an automatic brake valve, a valve casing having a main passage therein, a normally open valve controlling said passage, an exhaust passage extending from one side of the main passage, a normally closed exhaust valve controlling said exhaust passage, a fluid-actuated device controlling operation of said valves, means for conducting fluid under pressure to said fluid-actuated device, a supplemental exhaust passage extending from the exhaust side of the main passage, a normally closed valve controlling said supplemental exhaust passage, a fluid-actuated device controlling the supplemental exhaust valve, and means for conducting fluid under pressure to said last-mentioned fluid-actuated device.

10. In an automatic brake valve, a valve casing having a main passage therein, a normally open valve controlling said passage, an exhaust passage leading from one side of the main passage, a normally closed exhaust valve controlling said exhaust passage, means normally holding the exhaust valve closed and the main valve open, a fluid-pressure-actuated device connected with said valves, means for conducting fluid under pressure to said device whereby to close the main valve and open the exhaust valve, a supplemental exhaust passage extending from the exhaust side of the main

passage, a normally closed valve controlling said supplemental exhaust passage, means acting on said valve to normally hold the same closed, a fluid-pressure-actuated device connected with the supplemental exhaust valve, and means for conducting fluid under pressure to said device whereby to open the supplemental exhaust valve.

11. In an automatic brake valve, a valve casing having a main passage therein, a normally open valve controlling said passage, an exhaust passage extending from one side of the main passage, a normally closed exhaust valve controlling said exhaust passage, a fluid-actuated device controlling operation of said valves, means for conducting fluid under pressure to said fluid-actuated device, and means for governing the speed of movement of the fluid-actuated device.

12. In combination, a valve casing having a main passage therein, a valve controlling said main passage, an exhaust passage extending from one side of the main passage, an exhaust valve controlling said exhaust passage, a valve stem on which said valves are mounted, a piston on the end of the valve stem, a cylinder within which said piston works, means for conducting fluid under pressure to said piston, and means for governing the rate of movement of said piston.

13. In combination, a valve casing having a main passage therein, a valve controlling said main passage, an exhaust passage extending from one side of the main passage, an exhaust valve controlling said exhaust passage, a valve stem on which said valves are mounted, a piston on the end of the valve stem, a cylinder within which said piston works, means for conducting fluid under pressure to said piston, pressure relieving ports in the cylinder aforesaid, and means for governing the escape from said pressure relieving ports.

14. In combination with a valve casing having a main passage therein, a cylinder connected with the valve casing, a piston working in said cylinder, a valve connected with the piston and arranged to control the main passage, a member connected with the valve casing having an exhaust passage therein in communication with one side of the main passage in the valve casing, a valve disposed in the exhaust passage in the member aforesaid to control said exhaust passage, and a diaphragm within the said member arranged to control the exhaust valve.

15. In combination, a valve casing having a main passage therein, a normally open valve controlling said passage, an exhaust passage communicating with one end of the main passage, a normally closed valve controlling said exhaust passage, a fluid-actu-

- ated device controlling operation of said valves, a supplemental exhaust passage leading from the same end of the main passage as the first exhaust passage, a normally closed valve controlling said supplemental exhaust passage, and a fluid-actuated device controlling operation of said supplemental exhaust valve.
16. In an air brake valve adapted to be operably connected in a train pipe supply and to a service application and emergency application pipe, the combination of a valved casing directly connected in said train pipe supply, a piston connected with the valve thereof and operated by pressure from the service application pipe to close the train pipe valve, an emergency valve casing having two separated chambers, one in communication with the emergency application pipe and the other with the train pipe supply through the valve casing, and a valve operated upon by the fluid pressure from the emergency pipe to open the valve and permit the escape of pressure fluid from the train pipe supply to the open air to set the brakes.
17. The herein described air brake valve, comprising three sections coupled together, the lower section being connected in a train pipe supply, a stem mounted to reciprocate in all of the sections, a piston connected to the upper end thereof and in the upper section, said upper section being connected with a service application pipe, a valve carried at the lower end of the stem to control the pressure fluid through the lower section and train pipes, the central section being provided with an escape port and a central bore through which the stem passes, a valve at the juncture of the lower and central sections, an emergency cylinder provided with an escape port and also in communication with the central section and the lower section, and a valve mounted in said cylinder adapted to be operated by pressure from the emergency application pipe to open the valve and the communication between the lower section and the emergency cylinder.
18. The herein described air brake valve, comprising a main body having a piston chamber at its upper end connected with a service supply pipe, a valve controlled chamber at its lower end forming a connection between the train pipe sections, and with a central bore having an escape outlet, a stem mounted in said bore and extending into both chambers, a piston on the stem in the piston chamber and a valve upon the lower end in the lower chamber, an emergency cylinder divided into two chambers by a flexible partition having its inner chamber in communication with the lower section of the body and its inner chamber in communication with an emergency application fluid supply pipe, and a valve for controlling the communication between the inner chamber of the emergency cylinder and the main body opened by pressure from the emergency application supply pipe upon the flexible partition.
19. The herein described air brake valve, comprising a main body having a valve controlled from the service supply pipe, a valve controlled escape outlet, and a piston chamber for operating the valves, an emergency cylinder, a diaphragm dividing said cylinder into two chambers, one of the chambers being in communication with the main body of the valve and the other being in communication with an emergency fluid supply pipe, and a valve for normally closing the communication between the cylinder and the body of the valve in operable relation to the diaphragm, whereby the diaphragm by the action of pressure of the emergency pressure fluid thereon operates the valve to open communication with the body of the valve.
20. An air brake valve, comprising a main body having a valve casing, a piston cylinder and a coupling provided with a central bore and escape outlet, said piston cylinder having an inlet connected to the service application pipe, a valve for closing the opening in the valve casing, a stem connected with said valve and operating through the central bore of the coupling, a valve intermediate of the ends of the stem for controlling communication with the escape outlet and the valve casing, a piston arranged to operate in the cylinder and attached to the stem, a spring surrounding the stem and exerting an upward pressure upon the piston to normally hold the main valve open and the intermediate valve seated, and an emergency valve chamber having an escape outlet in communication with the main valve casing and operated by fluid from the emergency pipe to open communication with its outlet and the valve casing.
21. In an air-brake valve adapted to be operably connected in a train pipe supply, the combination of a casing directly connected in said supply, a valve controlling the supply through the casing, a cylinder, a piston mounted in said cylinder and adapted to be actuated by pressure from the service application pipe to close the valve, and means for relieving the pressure upon the piston to regulate the movement of the piston in closing the valve.
22. In an air-brake valve, adapted to be operably connected in a train pipe supply, the combination of a casing directly connected in said supply, a valve controlling the supply through the casing, a cylinder, a piston mounted in said cylinder and adapted to be actuated by pressure from the service application pipe to close the valve, and adjustable means for relieving the pressure

upon the piston to regulate the movement of the piston in closing the valve.

23. In an air-brake valve, adapted to be operatively connected in a train pipe supply, 5 the combination of a casing directly connected in said supply, a valve controlling the supply therethrough; a cylinder having a bypass in its wall and an outlet to the outside air, and a valve mounted in said by-pass 10 having ports above and below the piston when in normal position and closed by the piston when the valve is closed.

24. Air brake controlling means comprising a normally open valve interposed in the 15 train line, two normally closed exhaust valves controlling communication with the train line and outside atmosphere, means connected to the service application pipe for controlling the train line valve and one of 20 the exhaust valves, and means connected to

the emergency application pipe for controlling the other of said exhaust valves.

25. In combination, a valve casing having a main passage therein, a valve controlling said passage, an exhaust passage communicating with one end of the main passage, an exhaust valve controlling the exhaust passage, means for operating said valve whereby when the one valve has been opened the other will be closed, a supplemental exhaust 25 passage extending from the same end of the main passage as the first exhaust passage, a supplemental exhaust valve controlling said supplemental exhaust passage, and means controlling operation of said supplemental exhaust valve. 30 35
